US0D1071252S

(12) **United States Design Patent** (10) **Patent No.:** **US D1,071,252 S**
(45) **Date of Patent:** **** Apr. 15, 2025**

(54) **BUILDING MATERIAL**

(71) Applicant: **Blue Nordic GmbH**, Brienz (CH)

(72) Inventor: **Tom Andresen**, Algarve (PT)

(73) Assignee: **Blue Nordic GmbH**, Brienz (CH)

(**) Term: **15 Years**

(21) Appl. No.: **29/806,964**

(22) Filed: **Sep. 8, 2021**

Related U.S. Application Data

(62) Division of application No. 35/508,917, filed on Sep. 27, 2019 (U.S. filing date under 35 U.S.C. 384), and having an international filing date of Sep. 27, 2019, now Pat. No. Des. 940,906.

(30) **Foreign Application Priority Data**

Mar. 28, 2019 (EM) 006352332

OLSON & BEAR LLP

(57) **CLAIM**

The ornamental design for building material as shown and described.

DESCRIPTION

1.-4. Building material

3.1: Perspective

3.2: Front

3.3: Back

3.4: Left

3.5: Right

3.6: Top

3.7: Bottom

3.9: Reference

3.10: Reference

3.11: Reference

4.1: Front

4.2: Right

4.3: Back

4.4: Top

4.5: Left; and,

4.6: Bottom.

The double dot-dashed lines shown in the reproductions **3.2** to **3.5**, **4.1** to **4.3** and **4.5** are only to indicate an omitted length and form no part of the claimed designs; reproductions **3.8** to **3.11** are reference views showing the state in use of the claimed

1 Claim, 13 Drawing Sheets
